THE NORRIS PETERS CO., PHOTO-LITHO., WASHINGTON, D. C.

UNITED STATES PATENT OFFICE.

WILLIAM H. REIFF, OF PHILADELPHIA, PENNSYLVANIA, ASSIGNOR OF ONE-HALF TO HENRY F. McDOWELL, OF SAME PLACE.

BURGLAR-ALARM.

SPECIFICATION forming part of Letters Patent No. 499,365, dated June 13, 1893.

Application filed February 19, 1892. Renewed March 7, 1893. Serial No. 464,946. (No model.)

To all whom it may concern:

Be it known that I, WILLIAM H. REIFF, of the city and county of Philadelphia and State of Pennsylvania, have invented an Improvement in Burglar-Alarms, of which the following is a specification.

My invention relates to burglar alarms and consists of certain improvements which are fully set forth in the following specification and shown in the accompanying drawings which form a part thereof.

More particularly my invention relates to portable burglar alarms and consists of certain improvements in construction and arrangement of parts whereby the device is rendered more convenient and efficient.

My invention includes certain improvements in the devices for detachably attaching the apparatus in operative position to the frame of a door or window.

The invention also relates to the employment with the alarm apparatus of a cartridge magazine; and to other improvements and combinations of parts which are hereinafter more fully set forth and claimed.

In the drawings:—Figure 1 is a perspective view of a portable burglar alarm embodying my improvements. Fig. 2 is a longitudinal sectional view of the same attached to the frame of the door. Fig. 3 is a side elevation of the same showing it detached from the door frame. Fig. 4 is a transverse vertical sectional view on the line $x-x$ of Fig. 3. Fig. 5 is a plan view of the device; and Fig. 6 is a side elevation of the device, with the cartridge magazine partly open.

A is the case or shell provided with a cap or cartridge bore or seat a , which preferably extends through one end of the case or shell as shown. By having the bore or seat a open in this manner, a louder sound is obtained and the possibility of the injury of the parts from the explosion is prevented.

B is a hammer pivoted at b within a recess of the shell or case A and having its end in position to strike the cap or cartridge when supported in the bore or seat a . The hammer B is adapted to be opened as shown in Fig. 1.

D is a spring for actuating the hammer B when moved by the door or other object in the usual manner.

E is an attaching screw or pin received in a socket and movable longitudinally therein. The screw E is also removable from the socket e so that it may be left attached to the door 55 or window frame as shown in Fig. 3 and the case A removed.

F is a set screw for clamping the attaching screw E in any position, either when drawn out for attachment to the door or window 60 frame, as shown in Fig. 2, or when pushed wholly in, as in Figs. 5 and 6.

G is a cartridge or cap magazine carried by the case or shell A and containing one or more cartridges or caps g . While it is immaterial 65 to my invention in what particular manner this cartridge magazine is constructed and arranged in connection with the shell or casing A, I prefer to construct it as shown in Figs. 1, 3, 4, 5, and 6, in which it consists of a box 70 H pivoted as at h to the body of the shell or casing A. This box H may be locked in any convenient manner, as by the pin c and elongated slot d . The box H may be pivoted at h with sufficient looseness to permit the free 75 end to be lifted sufficiently to let the pin c pass through the slot d when the box is to be unlocked.

In Fig. 2, I have shown the cartridge magazine formed in an extension or continuation 80 of the socket e .

I is a plate pivoted and held by a set screw J to the body of the shell or casing A, by which the device may be attached to a window or door frame instead of by the screw E, when 85 the position of the screw is not suitable to the direction in which the door or window would open.

In applying the device, the screw E is drawn out, and having been clamped by the set screw 90 F, it is screwed into the door frame K adjacent to the jamb; the hammer B is raised so as to be in the path of the opening door L, as shown in dotted lines in Fig. 2, and a cap or cartridge is placed in the bore a . Any movement of the door L will strike the hammer and move it sufficiently to permit the spring D to act upon the hammer and snap it upon the cap or cartridge.

During the daytime, or whenever it may be 100 unnecessary to use the alarm, the case A may be removed leaving the screw E in the frame,

ready for the attachment of the case A when it is again desired to use the apparatus.

With the cartridge magazine constituting a part of the apparatus, there will always be 5 a cap or cartridge at hand when required; and while the apparatus is not in use the cartridge or cap may be removed from the bore or seat *a* and placed in the magazine.

While I prefer the minor details of construction which have been shown, I do not mean to limit my invention thereto, as it is apparent that they may be varied, but

What I claim as my invention is as follows:

1. A portable burglar alarm consisting of 15 an outer case or shell provided with a cartridge seat and having a longitudinal socket, an attaching screw movable longitudinally in said socket, means to clamp the screw in any desired position and a spring actuated 20 hammer.

2. As a new article of manufacture, a portable alarm consisting of the case A provided with the seat *a* and the socket *e*, the attaching screw *E* movable longitudinally in the 25 socket *e* and removable therefrom, and the clamping screw *F* for clamping the screw *E* in any desired position.

3. As a new article of manufacture a port-

able alarm consisting of the shell or case A having a seat *a*, the spring actuated hammer 30 *B*, carried by the shell or case and the plate *I* pivoted to the case A.

4. As a new article of manufacture a portable alarm consisting of the shell or case A having a seat *a*, the spring actuated hammer 35 *B*, carried by the shell or case the plate *I* pivoted to the case A, and set screw *J* adjacent to the plate *I*.

5. As a new article of manufacture a portable alarm consisting of a shell or a case A 40 having a seat *a* adjustable attaching screw *E*, carried by the shell or case A spring actuated hammer *B*, and plate *I* pivoted to the shell or case A.

6. A burglar alarm consisting of the shell 45 or case A, spring actuated hammer *B*, cartridge box *H* pivoted to the shell or case A and having the elongated slot *d*, and the locking pin *c*.

In testimony of which invention I have here- 50 unto set my hand.

WILLIAM H. REIFF.
